UNITED STATES PATENT OFFICE.

CHARLES BERGMANN, OF PITTSBURG, PENNSYLVANIA, ASSIGNOR OF TWO-FIFTHS TO J. E. O'SHEA, OF SAME PLACE.

AUTOMATIC BRAKE-SETTING AND SIGNALING APPARATUS.

SPECIFICATION forming part of Letters Patent No. 655,184, dated August 7, 1900.

Application filed April 26, 1900. Serial No. 14,479. (No model.)

To all whom it may concern:

Be it known that I, CHARLES BERGMANN, a citizen of the United States, residing at Pittsburg, in the county of Allegheny and State of Pennsylvania, have invented a new and useful Automatic Brake-Setting and Signaling Apparatus, of which the following is a specification.

This invention relates to a safety appliance for railway-trains, and has special reference to an automatically-operating brake-setting and signaling apparatus associated with the fluid-pressure or air brake system of the train and designed to automatically provide for setting the brakes and simultaneously notifying the engineer upon a train coming into dangerous proximity to a succeeding train or to an obstruction across the track of such a nature as would close the track-circuits forming a part of the apparatus.

To this end the invention has in view the provision of a novel and efficient brake-setting and signaling apparatus which provides means for automatically applying the brakes and notifying the engineer of the necessity of closing the throttle whenever two or more trains enter upon the same block or section from the same or opposite directions or approach within a given distance of the termini of two adjacent blocks or sections. In one of its special applications the apparatus provides means for automatically setting the brakes should one train be departing from a block at the time a second train is entering the same block. With this condition existing the brakes of the second or following train which is entering the block will be automatically set and the engineer notified, while the brakes of the first train departing from the same block will be unaffected, so that the movement of said train will not be interfered with.

In carrying out the invention one of the special objects thereof is to associate the air-controlling mechanism of the apparatus with the pipe leading from the main reservoir to the engineer's brake-valve, so that when the said air-controlling mechanism is set into action to release the air from the train-line or "brake-pipe," as it is commonly termed, the supply of air from the main reservoir will be

cut off entirely from the engineer's brake-valve, so that the engineer will have no control whatever of the excess pressure of air in the main reservoir, and therefore by the manipulation of the brake-valve could not release the brakes, and the said brake-valve can only be operated to release more air from the train-line, and thus secure a tighter setting of the brakes.

Heretofore devices have been provided in connection with the ordinary air-brake system to provide for automatically releasing or exhausting the air from the train-line or brake-pipe to insure an automatic setting of the brakes when trains are in unsafe proximity to each other; but in all of such devices the air-release mechanism has been arranged at some point between the engineer's brake-valve and the equipment for each car or vehicle, and therefore does not interfere with a direct connection between the main reservoir and the engineer's brake-valve, thus giving the engineer power to throw the excess pressure from the main reservoir into the train-line or brake-pipe, and thus release the brakes. The present invention, however, entirely obviates this possibility by simultaneously cutting off communication between the engineer's brake-valve and the main reservoir at the time of releasing or exhausting air from the main train-line or brake-pipe.

With these and many other objects in view, which will readily appear to those familiar with the art as the nature of the invention is better understood, the same consists in the novel construction, combination, and arrangement of parts hereinafter more fully described, illustrated, and claimed.

The essential features of the invention, involving the special construction of the air-controlling mechanism and the novel arrangement thereof at a point between the main reservoir and the engineer's brake-valve, are necessarily susceptible to some modification without departing from the spirit or scope of the invention; but the preferred embodiment of the improvements is shown in the accompanying drawings, in which—

Figure 1 is a diagrammatic view of that portion of a fluid-pressure brake system of the Westinghouse type which is applied to

the locomotive, showing the preferred arrangement of the air-controlling mechanism in the line of the pipe connection between the main air-reservoir and the engineer's brake-valve. Fig. 2 is a diagrammatic plan view showing the preferred arrangement of the blocks and track-circuits designed for automatically actuating the air-controlling mechanism constituting the improvement sought 5 to be covered. Fig. 3 is a diagrammatic view of the track, showing a greater number of blocks to more clearly illustrate the manner of connecting in the same circuit opposite rails of alternating blocks. Fig. 4 is a side 10 elevation, partly in section, of the air-controlling mechanism, showing the same in action to cut off the main reservoir from the engineer's brake-valve and permitting the air to exhaust or escape from the train-line or 15 brake-pipe. Fig. 5 is a complete sectional view of the air-controlling mechanism, illustrating the normal or at-rest position thereof, with the line of communication between the main reservoir and the engineer's brake-valve 20 uninterrupted. Fig. 6 is a detail sectional view of the air-release valve forming a part of the said air-controlling mechanism. Fig. 7 is a cross-sectional view on the line 7 7 25 of Fig. 5, showing the connection of the bypass with the casing for the plunger-valve and the relative positions of the air inlet and the exhaust ports of the said casing.

Like characters of reference designate corresponding parts in the several figures of the 30 drawings.

In carrying out the present invention it is necessary to provide, in connection with the track, suitable normally-open circuits which may be closed at proper points through the 35 axle of the train or trains, and while any particular arrangement of track-circuits in connection with the usual "blocks" is not necessary to the successful carrying out of the invention, still the preferred way of wiring the blocks is shown in Figs. 2 and 3 of the drawings. The blocks of the railway-track are of the usual lengths and are designated by the reference-letters A, B, C, and D; but to insure a successful operation of 40 the apparatus claimed herein the contiguous ends of adjoining blocks are insulated, as at I, and overlap, whereby the rail of one block will project partly into an adjacent block, so that the locomotive of a train will enter upon a succeeding block, while the larger portion of the 45 said train remains within the immediately-preceding block. This arrangement becomes important to provide for automatically applying the brakes to the train which enters the block 50 from which another train has just departed, as will be hereinafter more fully explained; but the necessary action of the apparatus may be effected by including alternately in a normally-open incomplete circuit the blocks 55 A and C, B and D, &c. The said circuit for A and C is designated by the characters *a* and *c*, and the circuit for the blocks B and D

by the letters *b* and *d*, as plainly shown in Fig. 3 of the drawings, and each of said normally-open incomplete circuits includes a battery 1 or other source of electrical energy. It will be observed that the circuit-wire *a* leads from one pole of the battery to one rail of the block A, while the wire *c* for the same circuit leads from the other pole of the battery to the opposite rail of block C. This order is preserved throughout the entire track and is substantially the same system of wiring as disclosed in Patent No. 522,757. It is therefore understood that the system of wiring is shown simply for illustrative purposes and is not claimed herein, as any equivalent system could be employed that would secure the desired operation of the air-controlling mechanism.

A detailed description of the fluid-pressure or air brake system of the train is unnecessary, as the present invention is designed for use in connection with the ordinary system, commonly known as the "Westinghouse" 80 air-brake system, in which the brakes are automatically applied by exhausting or releasing the air from the main train-line or brake-pipe either from the engineer's brake-valve or at any other point in the line thereof. 90 This system involves the employment of an ordinary brake-valve 2, which is usually arranged in the cab of the locomotive and has a direct pipe connection 3 with the main reservoir 4, which receives its supply of air from the air-pump 5, operated and controlled in the usual manner. The engineer's brake-valve 2 also has connected therewith the main train-line or brake-pipe 6, which communicates with the apparatus of the entire train—that is, the triple valve, auxiliary reservoir, and brake-cylinder of each car. These parts are common appurtenances of the Westinghouse air-brake system and need not be illustrated or described, as it is well understood 100 that the automatic action of the brakes is due to the action of the triple valve in connection with the auxiliary reservoir and brake-cylinder associated therewith and that a reduction of air-pressure in the train-line or brake-pipe 105 causes the greater pressure remaining stored in the auxiliary reservoir to force the piston of the triple valve and its slide-valve to a position which will allow the air in the auxiliary reservoir to pass directly into the brake-cylinder 110 to apply the brake. In the action of the air-brake system when the pressure in the train-line or brake-pipe is again restored to an amount in excess of that remaining in the auxiliary reservoir the triple 115 valve is actuated to open up communication again with the auxiliary reservoir and to permit the air in the brake-cylinder to escape, thus releasing the brakes. In other words, the excess pressure in the main reservoir is utilized by the engineer when it is desired to actuate the triple valve for releasing the brakes, and therefore if the excess pressure in the main reservoir is cut off 120

from the control of the engineer it is impossible for him to release the brakes by manipulating the engineer's brake-valve 2. It is for this very purpose that the present invention contemplates the positioning of the air-controlling mechanism (designated in its entirety by the letter M) in the line of the pipe 3 between the main reservoir 4 and the engineer's brake-valve 2, as plainly shown in Fig. 1 of the drawings. This air-controlling mechanism involves means for automatically releasing or relieving the air-pressure in the train-line or brake-pipe and simultaneously cutting off communication with the main reservoir, and the instrumentalities for accomplishing these results will now be especially pointed out. The said air-controlling mechanism M includes a main-valve casing 7, having the opposite coupling-necks 8 and 8^a, to which are respectively coupled the separate portions of the pipe 3, leading to the main reservoir and the engineer's brake-valve 2, and the said main-valve casing 7 is provided with an interior ported valve-seat 9, which when uncovered leaves a free communication through the casing to the separate portions of the reservoir-pipe 3, as plainly illustrated in Fig. 5 of the drawings. The said interior ported seat 9 of the main-valve casing 7 is adapted to be covered and uncovered by one of a pair of spaced cut-off valves 10 and 10^a, working within the casing-neck 11, projected from one side of the casing 7 in transverse alignment with the ported valve-seat 9. The said cut-off valves 10 and 10^a are arranged in spaced parallel relation and are carried at one end of a reciprocatory main-valve stem 12, which slidably works through guide-openings 13 at opposite ends of the air-escape chamber 14, which is interposed between the main-valve casing 7 and one end or side of the enlarged piston-chamber 15. The said interposed air-escape chamber 14 is of a larger interior diameter than the diameter of the reciprocating valve-stem 12, and at the end opposite its connection with the enlarged piston-chamber 15 the said air-escape chamber 14 is provided with a valve-seat 16, exposed within the valve-casing neck 11 and provided therein with a plurality of air-ports 17, which when uncovered provide a direct communication with the interior of the valve-casing 7 at one side of its seat 9 and the interior of the air-escape chamber 14. The ported valve-seat 55 at one end of the chamber 14 is designed to be covered and uncovered by the outer cut-off valve 10^a, which is spaced from the terminal cut-off valve 10, which co-operates with the main-valve seat 9 of the casing 7, and at this point it is to be observed that each of the cut-off valves 10 and 10^a is faced with a gasket 18, preferably of vulcanized sponge-rubber, which best insures an air-tight seating of the valve without possibility of sticking to the valve-seat or otherwise becoming impaired; but it will of course be understood that other suitable packing may be applied

to the working faces of the valves 10 and 10^a. It is to be noted that the gaskets or working faces of the valves 10 and 10^a are arranged in reversed relation, so that when the stem 12 is moved in one direction the valve 10 will be carried onto its seat 9 and when the stem is moved in the opposite direction the valve 10^a will be carried onto the seat 16 to provide for covering the air-port 17 therein.

The air-escape chamber 14 preferably has a suitable threaded-coupling connection 19 with the casing-neck 11; but it is obvious that any mechanical expedient may be resorted to for properly connecting the said air-escape chamber with the main-valve casing 7, and the same is true of the connection between the said air-escape chamber and the piston-chamber 15, although the preferable manner of combining these elements is shown in the drawings and consists in providing the end cap 20 for one end of the said chamber 15 with an exteriorly-threaded collar 21, fitted in a correspondingly-threaded socket at one end of the chamber 14 and forming a closure therefor, besides providing for the coupling together of the parts.

At a point intermediate its ends the air-escape chamber 14 is provided with an air-vent 22, opening through a coupling-neck 23, which supports an exhaust-chamber 24, constituting not only a chamber for the exhaust of air from the train-line, but also acts in the capacity of a casing for the air-release valve 25. The said exhaust-chamber 24 is preferably formed of two tubular casing-sections 24^a 24^b, interiorly threaded to receive therein an exteriorly-threaded tubular nut 26, which tubular nut is designed to extend across the joint at the meeting edges of the sections and provides means for coupling the said sections together, besides serving the important function of a regulating-nut for adjusting the tension of the spring 27, arranged upon the stem 28 of the air-release valve 25. The stem 28 is projected from one side of the air-release valve 25 and is guided in its movements by the guide-bore 29, formed in one end portion of the nut 26, the opposite end portion of which is provided with the air-passage 30, through which the air escapes into the extreme outer end portion of the outermost casing-section 24^b and thence through the outlet-port 31 into the signal-whistle 32, from which it escapes into the outer air. The inner end portion of the adjustable tubular nut 26, which receives the stem 28 of the air-release valve 25, bears upon one end of the spring 27, the other end of which spring bears against one side of the valve 25 to provide for normally holding the same upon the ported seat 33, arranged at the extreme inner end of the exhaust-chamber or valve-casing 24. The ported seat 33 is preferably provided on the coupling-neck 23 and is provided with a central guide-opening 34 to receive the lower stem portion 35 of the valve 25, and at this point it is to be observed that the said valve

25 has fitted to the working face thereof a gasket 36, of the same material as the gaskets 18, for the working faces of the cut-off valves 10 and 10^a.

5 With reference to the spring 27 for the air-release valve 25, this spring is adjusted so that the said valve will open at any desired working pressure, according to the distance within which it may be predetermined the 10 train should stop, and therefore when communication is cut off from the main reservoir by the valve 10 being closed upon its seat 9 the pressure in the train-line or brake-pipe will reduce commensurate with the tension 15 or adjustment of the spring 27, thus providing means for regulating the application of the brakes.

The piston-chamber 15 accommodates for movement therein a valve-actuating piston 20 37, which is of a materially-greater area than the cut-off valves 10 and 10^a, and said valve-actuating piston 37 is mounted on the end of the valve-stem 12 opposite the cut-off valves and is designed to provide means when moved 25 under the pressure of air in one direction to unseat the valve 10^a and at the same time to seat the valve 10 to cut off communication from the main reservoir, and to assist in the reclosing of the valve 10^a and the adjustment 30 of the valve-actuating piston 37 to a normal position a readjusting-spring 38 is coiled around the stem 12 and interposed between one side of the piston 37 and the end cap 20 of the piston-chamber.

35 The piston-chamber 15 is provided at the end or side opposite its connection with the air-escape chamber 14 with the combined supply and exhaust passage 39, which is in communication with one end of a plunger-valve casing 40, preferably in the form of a sleeve and detachably coupled, by means of a screw or equivalent joint 41, to the said piston-chamber 15. The said plunger-valve casing or sleeve 40 is coupled at the end opposite its connection with the piston-chamber 15, as at 42, with one side of a magnet-case 43. This magnet-case is preferably provided at one side or end thereof with a detachable cap or cover 44 to render the parts therein accessible for repair or adjustment, and housed within and suitably insulated from the said case 43 is a controlling-magnet 45, having connected therewith the binding-posts 46, located exterior to the case 43, and adapted to 45 have play over one end of the magnet is the armature 47. The armature 47 is preferably held to a fixed movement by loosely working over the fixed guide-pins 48, projecting from one end of the magnet-body, and said armature 50 is rigidly fastened by any suitable means to the outer end of the plunger-valve 49 in the form of a stem or rod working through the central bore or core 50 of the magnet and also extending into and slidably 60 working within the plunger-valve casing or sleeve 40.

The plunger-valve 49 has imparted thereto

from the magnet 47 a movement in one direction and is moved in the opposite direction so as to be carried to a normal at-rest position through the medium of the retracting or setting spring 50^a, which is coiled upon the reduced portion of the plunger-valve at the extreme inner end thereof, and has its opposite ends bearing, respectively, against the shoulder 51 of said reduced portion and the adjacent side of the piston-chamber to which the valve casing or sleeve is coupled. The stem or rod 49 performs the function of a plunger-valve by reason of the same being provided within its inner end portion with a longitudinally-disposed air-passage 52, which is always in communication with the combined supply and exhaust passage 39 of the piston-chamber 15, and the said air-passage 52 of the plunger-valve 49 has communicating therewith the inlet and exhaust ducts 53 and 54, respectively, which pierce the valve 49 laterally and are disposed in different transverse planes, whereby the said ducts may be 90 separately brought into action. Both of the ducts 53 and 54 extend to the outer wall of the valve 49, while their inner ends are in direct communication with the longitudinal air-passage 52 of the valve, and the inlet-duct 95 53 of said valve is designed to be moved in and out of communication with the air-inlet port 55, formed in one side of the plunger-valve casing or sleeve 40 and communicating with one end of the by-pass pipe 57, which 100 end of the by-pass pipe is suitably joined or coupled to the valve casing or sleeve 40, and the other end of which pipe is connected with that portion of the reservoir-pipe 3 lying between the main-valve casing 7 of the 105 apparatus and the main reservoir 4 of the air-brake system, thus providing means when the duct 53 is brought in communication with the air-inlet port 55 for air to escape from the main reservoir into the piston-chamber 15 at one side of the valve-actuating piston 37 therein. The air-exhaust duct 54, which is in a different plane from the inlet-duct 53, is designed to be moved in and out of register with the exhaust-port 58, also formed 110 in one side of the plunger-valve casing 40, and in communication with the blow-off whistle 59, suitably fitted to the casing 40, and not only providing for exhausting such air as is permitted to pass through the port 115 58, but also acting in the capacity of a safety or "O K" signal, which sounds after the brakes have been released and the parts of the apparatus permitted to resume normal positions. In the normal position of parts, 120 when the handle of the engineer's brake-valve is set in position for running, the parts of the air-controlling mechanism are in such positions as to permit of a free communication through the pipe 3 and the main-valve 125 casing 7 between the main reservoir 4 of the system and the engineer's brake-valve, so that the engineer may manipulate the latter in the usual way to meet ordinary con-

ditions. Hence in the normal position of the parts of the air-controlling mechanism the readjusting-spring 38, together with the pressure of air in the reservoir - pipe 3 and 5 main-valve casing 7, holds the cut-off valve 10^a firmly to its seat 16, thereby covering the air-port 17 and cutting off communication between the interior of the main-valve casing 7 and the air-escape chamber 14. The 10 air-release valve 25 is also relieved from air-pressure, and the spring 27 holds the same to its seat 33 to cover the ports therein. Also the retracting or setting spring 50 for the plunger-valve 49 holds the armature 47 15 away from the adjacent end of the controlling-magnet 45, with the exhaust-duct 54 in communication with the exhaust-port 58, and the inlet-duct 53 out of register with the inlet-port 55, which communicates with the by-pass pipe 57. The parts remain in these normal positions until a circuit is closed through the controlling-magnet 45 by the train reaching a position where it should be stopped. This condition will necessarily vary according 20 to the particular arrangement of blocks and track-circuits which may be adopted; but for purposes of illustration it is shown in the drawings that when a train is entering a block the air-controlling mechanism thereof 25 will be actuated if the succeeding train has not entirely passed out of the same block. This relation of the two trains is plainly shown in diagrammatic Fig. 2 of the drawings, and, referring particularly to this figure, T No. 1 30 designates the first train which is passing out of block B into block C, and one of the rear axles of said train is in metallic contact with one of the rails of the block C and the opposite rail of block B on account of the overlapping 35 relation of these rails. T No. 2 designates the following train just entering block B from block A, and the front axle thereof has entered entirely upon block B. With this position of the trains the circuit will be 40 closed from one pole of the battery 1 through wire *a*, one rail of block A, tender or last car-axle of T No. 2, wire *m*, leading from such axle to one of the binding-posts 46 of the controlling-magnet 45, magnet 45, through 45 the wire *m'*, connected with the other binding-post 46 for the magnet, the front axle of train No. 2, one rail of block B, axle of train No. 1, and wire *c*, and thence to battery 1. A 50 circuit is therefore closed through the controlling-magnet 45, and the same result would be effected in the event of any metallic obstruction, such as a car, across the track in the same position as the axle of train No. 1. (Shown in Fig. 2 of the drawings.) When 55 a circuit is thus automatically closed by the system of wiring described or by any other approved system of track-circuits which may be adopted, the controlling-magnet 45 of the air-controlling mechanism is energized, and thereby attracts its armature 47. The movement of the armature is transmitted to the plunger-valve 49, which moves the exhaust-

duct 54 out of register and at the same time brings the inlet-duct 53 into communication with the by-pass pipe 57, whereupon the full 70 pressure of air from the main reservoir will be delivered from the by-pass pipe 57 into the air-passage 52 of the plunger-valve and thence into the piston-chamber 15. By reason of the greater impact area of the piston 75 37 as compared to the area of the cut-off valves 10 and 10^a a superior pressure will be exerted upon the piston 37, causing the unseating of the cut-off valve 10^a and the seating of the valve 10 upon the main-valve 80 seat 9 of the casing 7. This entirely cuts off the main reservoir from the engineer's brake-valve, and the air from the train-line or brake-pipe finds relief through said valve, the valve-casing 7, the air-ports 17 of the 85 valve-seat 16, the air-chamber 14, air-vent 22, past the air-release valve 25, through the tubular adjusting-nut 26, and thence through the blow-off whistle 32. Provision is thus made for immediately reducing the pressure 90 of air in the train-line or brake-pipe, and consequently permitting the air in the auxiliary reservoir to operate the triple valve so as to bring the auxiliary reservoir in communication with the brake-cylinder, and thus 95 secure an application of the brakes. At this point it may be stated again that the spring 27 is adjusted to any suitable working pressure, according to the distance within which the train is desired to be stopped upon the 100 automatic operation of the air-controlling mechanism.

With the engineer's brake-valve cut off from communication with the main reservoir the engineer is utterly unable to manipulate 105 the valve so as to release the brakes, inasmuch as it requires the superior or excess pressure in the main reservoir to secure the readjustment of the triple valve and open up communication from the train-line or brake-pipe to the auxiliary reservoir. Therefore 110 with the parts of the apparatus set in the positions described the only effective manipulation of the handle of the engineer's valve can be to either the "service" or "emergency" 115 stops, which, however, would secure a greater release of air with a consequent tighter setting of the brakes. This is an important feature of the invention, because the setting of the brakes is accomplished automatically 120 without any effort on the part of the engineer.

At the time communication is cut off between the main reservoir and the engineer's brake-valve and the train-line or brake-pipe pressure is reduced through the release-valve, the blow-off whistle 32 will sound an alarm as long as the air is escaping and the brakes being set, and consequently signals the engineer to shut off his throttle.

To make provision for the releasing of the 130 brakes, it is necessary to open a circuit through the controlling-magnet 45. This may be accomplished by arranging a suitable switch 60 in the line of the circuit for the mag-

net and preferably locating said switch in the engineer's cab for convenient control. When the track is again clear and the train may pass with safety, the engineer opens the switch 60, thereby opening the electrical circuit and causing a deenergization of the controlling-magnet 45. When this takes place, the retracting or setting spring 50 moves the inlet-duct 53 out of register with the port 55, and thus cuts off communication with the by-pass pipe 57, and at the same time the exhaust-duct 54 is brought into communication with the exhaust-port 58 and the blow-off whistle 59. Thereupon the readjusting-spring 38, assisted in a measure by the pressure of air upon the valve 10, moves the valve-actuating piston 37 outward, causing the unseating of the valve 10, the reseating of the valve 10^a, and the exhausting of the air from the piston-chamber through the blow-off whistle 59, thereby giving an "O K" signal to indicate that the apparatus is reset and the engineer is again in full control of the excess pressure of the main reservoir to actuate the triple valves, and thus provide for the release of the brakes.

From the foregoing it is thought that the construction, operation, and many advantages of the herein-described automatic brake setting and signaling apparatus will be readily apparent to those familiar with the art without further description, and it will be understood that various changes in the form, proportion, and minor details of construction may be resorted to without departing from the principle or sacrificing any of the advantages of this invention.

Having thus described the invention, what is claimed as new, and desired to be secured by Letters Patent, is—

1. In an apparatus of the class described, the combination with the engineer's brake-valve and main reservoir, of means, interposed between the main reservoir and the engineer's brake-valve, for automatically cutting off the excess pressure of said reservoir from the valve and simultaneously releasing the pressure in the train-pipe, substantially as set forth.

2. In an apparatus of the class described, the combination with the main reservoir and engineer's brake-valve of an air-brake system, of an air-controlling mechanism connected with the pipe between the reservoir and the brake-valve, and having means for automatically cutting off communication between the reservoir and said valve, and simultaneously releasing the pressure in the train-pipe, substantially as set forth.

3. In an apparatus of the class described, the combination with the main reservoir and the engineer's brake-valve of an air-brake system, of an air-controlling mechanism connected with the reservoir-pipe between the main reservoir and the brake-valve, and having means for automatically cutting off communication between the reservoir and said valve,

and simultaneously releasing the pressure in the train-pipe and sounding a continuous alarm during such release of the air-pressure, substantially as set forth.

4. In an apparatus of the class described, the combination with the main reservoir and the engineer's brake-valve of an air-brake system, of an air-controlling mechanism interposed between the main reservoir and said valve and having means for automatically cutting off communication between the reservoir and the brake-valve and simultaneously releasing the pressure in the train-pipe, said mechanism also having means for sounding a continuous alarm during the releasing of the air-pressure in the train-pipe, and a separate alarm or signal upon the restoration of communication between the main reservoir and the engineer's brake-valve, substantially as set forth.

5. In an apparatus of the class described, an air-controlling mechanism interposed between the main reservoir and the engineer's brake-valve of an air-brake system, and having a main-valve casing provided with a through passage-way and with air-escape ports, a pair of cut-off valves arranged respectively to close the through passage-way and said air-escape ports, and common means for automatically actuating said valves, substantially as set forth.

6. In an apparatus of the class described, an air-controlling mechanism having a main-valve casing interposed in the pipe between the main reservoir and the engineer's brake-valve of an air-brake system, said valve-casing being provided with an interior ported seat, and beyond and in the transverse plane of said seat, with air-escape ports, a pair of spaced cut-off valves arranged to reciprocate within the valve-casing and adapted to respectively cover said ported seat and the air-escape ports, and common means for automatically actuating said valves to alternately carry the same to and from their seats, substantially as set forth.

7. In an apparatus of the class described, an air-controlling mechanism having a main-valve casing fitted to the main-reservoir delivery-pipe of an air-brake system, and provided with an interior cut-off seat and with lateral air-escape ports, an air-release valve in communication with said ports, and a pair of automatically-actuated cut-off valves working within the main-valve casing and respectively coöperating with the interior cut-off seat and said air-escape ports, substantially as set forth.

8. In an apparatus of the class described, an air-controlling mechanism having a main-valve casing fitted to the main-reservoir delivery-pipe of an air-brake system, and provided with an interior cut-off seat and with lateral air-escape ports, an air-escape chamber in communication with said air-escape ports, an air-release valve connected with said air-escape chamber, and a pair of auto-

matically - actuated cut-off valves working within the main-valve casing and respectively coöperating with said interior cut-off seat and the air-escape ports, substantially as set forth.

- 5 9. In an apparatus of the class described, an air-controlling mechanism having a main-valve casing fitted to the main-reservoir delivery-pipe of an air-brake system, and provided with an interior cut-off seat and air-escape ports, an air-escape chamber in communication with said ports, a combined air-release valve and signal device connected with said air-escape chamber, and a pair of automatically - actuated cut-off valves working 15 within the main - valve casing and adapted to alternately cover respectively the interior cut-off seat and said air-escape ports, substantially as set forth.

10. In an apparatus of the class described, 20 an air-controlling mechanism comprising a main-valve casing fitted to the main-reservoir delivery-pipe of an air-brake system, and provided with an interior cut-off seat, air-escape ports, an air-escape chamber in communication 25 with said ports, a combined air-release valve and signal device connected with said air-escape chamber, said combination device being provided with an adjustable air-release valve, and a pair of automatically-actuated 30 cut-off valves working within the main-valve casing and respectively coöperating with said interior cut-off seat and said air-escape ports, substantially as set forth.

11. In an apparatus of the class described, 35 an air-controlling mechanism comprising a main-valve casing fitted to the main-reservoir delivery-pipe of an air-brake system, and provided with an interior cut-off seat and side air-escape ports, an air-escape chamber in 40 communication with said ports, automatically-actuated cut-off valves respectively for the interior cut-off seat and said ports, and a combined air-release and signal device connected with the air-escape chamber, said air- 45 release and signal device consisting of a casing having at one end a ported seat in communication with the air-escape chamber, a blow-off whistle at its opposite end, an air-release valve working over the ported seat, 50 and valve-regulating means within the casing, substantially as set forth.

12. In an apparatus of the class described, an air-controlling mechanism comprising a main-valve casing fitted to the main-reservoir 55 delivery-pipe of an air-brake system, and provided with an interior cut-off seat and side air-escape ports, an air-escape chamber in communication with said ports, automatically-actuated cut-off valves respectively for 60 the interior cut-off seat and said ports, and a combined air-release and signal device connected with the air-escape chamber, said air-release and signal device consisting of a sectional casing having a ported seat at one end 65 in communication with the air-escape chamber, a blow-off whistle at the opposite end, an air-release valve working over the ported

seat and having an extended stem, a regulating-spring arranged over the valve-stem and bearing at one end upon the valve, and a 70 tubular nut adjustably mounted within the casing and coupling the sections thereof together, said nut being arranged to bear upon the spring at one end thereof to regulate its tension, substantially as set forth.

13. In an apparatus of the class described, an air-controlling mechanism comprising a main-valve casing fitted to the main-reservoir delivery-pipe of an air-brake system, and provided with an interior cut-off seat and side 80 air-escape ports, cut-off valves respectively coöperating with the interior cut-off seat and said air-escape ports, and means for automatically uncovering the air-escape ports and closing the passage-way through the main- 85 valve casing by the direct pressure of the air from the main reservoir, substantially as set forth.

14. In an apparatus of the class described, an air-controlling mechanism comprising a 90 main-valve casing fitted to the main-reservoir delivery-pipe of an air-brake system, and having air-escape ports, and means for simultaneously uncovering the said air-escape ports to place the same in communication 95 with the engineer's brake-valve and closing the passage-way through the main-valve casing by the direct pressure of air from the main reservoir, substantially as set forth.

15. In an apparatus of the class described, 100 an air-controlling mechanism comprising a main-valve casing fitted to the main-reservoir delivery-pipe of an air-brake system, and having air-escape ports, valves for respectively closing the passage-way through the main- 105 valve casing and the said air-escape ports, means for utilizing the direct pressure of air from the main reservoir to uncover the air-escape ports and to close the passage-way through the valve-casing, and an electrically- 110 actuated valve for automatically admitting and cutting off the motive supply of air from the main reservoir for actuating the mechanism, substantially as set forth.

16. In an apparatus of the class described, 115 an air-controlling mechanism comprising a main-valve casing fitted to the main-reservoir delivery-pipe of an air-brake system, and provided with air-escape ports, the main-valve 120 stem carrying the valves for respectively covering the air-escape ports and the main cut-off seat of the valve-casing, a piston-chamber, a piston working within said chamber and fitted to said valve-stem, a by-pass connection with the main-reservoir delivery- 125 pipe for supplying air to the piston-chamber for actuating the valves in one direction, and an electrically-operated valve for automatically cutting off and opening up communication with the said by-pass connection, sub- 130 stantially as set forth.

17. In an apparatus of the class described, an air-controlling mechanism having a main- 135 valve casing fitted to the main-reservoir de-

livery-pipe of an air-brake system, and provided with air-escape ports, a main-valve stem carrying a pair of cut-off valves working within the main-valve casing, a piston-chamber, a valve-actuating piston working in said chamber and connected with the main-valve stem, a separate valve-casing connected with the piston-chamber and in communication therewith, a by-pass pipe connecting the said separate valve-casing with the main-reservoir delivery-pipe, and an automatically-actuated valve working within said separate valve-casing and arranged to cut off and open up communication with said by-pass pipe, substantially as set forth.

18. In an apparatus of the class described, an air-controlling mechanism comprising a main-valve casing fitted to the main-reservoir delivery-pipe of an air-brake system, and provided with air-escape ports, a main-valve stem carrying a pair of cut-off valves working in the main-valve casing and also carrying at the end opposite said valves, a valve-actuating piston, a reducing-spring arranged at one side of the said piston, a plunger-valve casing in communication with the piston-chamber, at one side of the piston therein, a blow-off signal fitted to the plunger-valve casing, a by-pass pipe connecting the main-reservoir delivery-pipe with said plunger-valve casing, and an automatically-operating and electrically-actuated plunger-valve working in said plunger-valve casing and provided with a longitudinal air-passage and separate air inlet and exhaust ducts adapted to respectively communicate with the by-pass pipe

and said blow-off whistle, substantially as set forth.

19. In an apparatus of the class described, an air-controlling mechanism comprising a main-valve casing fitted to the main-reservoir delivery-pipe of an air-brake system, and having air-escape ports, a main-valve stem carrying cut-off valves working within the main-valve casing, and also carrying a valve-actuating piston, a piston-chamber housing the said piston, a spring arranged at one side of the piston, a plunger-valve casing in communication with the piston-chamber, a magnet-case connected with the plunger-valve casing, a controlling-magnet housed within said magnet-case and having an armature, a blow-off whistle fitted to the plunger-valve casing, a by-pass pipe connecting the plunger-valve casing with the main-reservoir delivery-pipe, a reciprocating plunger-valve connected with the armature of the controlling-magnet, and provided with a longitudinal air-passage and with separate inlet and exhaust ducts adapted to respectively communicate with the blow-off whistle and said by-pass pipe, and a spring arranged to engage with the plunger-valve for moving the same in one direction, substantially as set forth.

In testimony that I claim the foregoing as my own I have hereto affixed my signature in the presence of two witnesses.

CHARLES BERGMANN.
